COMBINATION OIL AND GAS RANGE

Filed Nov. 18, 1940

UNITED STATES PATENT OFFICE

2,353,689

COMBINATION OIL AND GAS RANGE

William T. Caley, Kalamazoo, Mich., assignor to
Kalamazoo Stove & Furnace Company, Kala-
mazoo, Mich., a corporation of Michigan

Application November 18, 1940, Serial No. 366,133

8 Claims. (Cl. 126—39)

This invention relates to improvements in combination oil and gas ranges.

The main objects of this invention are:

First, to provide a combination oil and gas range of high thermal efficiency particularly in the matter of oven heating.

Second, to provide a cooking range embodying an oven with an oil burner heating unit in which the oven is very efficiently heated and one in which the heat within the oven is very uniformly distributed.

Third, to provide a structure of the class described including an oven which may be selectively heated by gas or an oil burner which is efficient in the use of either fuel.

Objects relating to details and economies of the invention will appear from the description to follow. The invention is defined and pointed out in the claims.

A structure which is a preferred embodiment of the invention is illustrated in the accompanying drawing, in which:

Fig. 1 is a fragmentary view partially in front elevation and partially in vertical section on line 1—1 of Figs. 2 and 3.

Fig. 2 is a fragmentary view partially in end elevation and partially in vertical section on line 2—2 of Fig. 1, showing certain details of the oil burner unit structure and the arrangement thereof within the oil burner combustion chamber.

Fig. 3 is a fragmentary view in section on a line corresponding to line 3—3 of Fig. 1.

The present invention relates to a combination liquid-gaseous fuel range wherein either gas or oil or a combination of the same are selectively employable as the heating media. This structure includes a gas heated oven associated in a novel manner in relation to an oil burner chamber, whereby the products of combustion of the said burner are employed to increase the efficiency of the oven and range as a whole or in supplement to the oven gas heating medium, the said oven being insulated in a manner to be very uniformly heated throughout without the occurrence of local "hot spots." Moreover, the invention comprehends an oil burning unit for the foregoing purposes which is selectively employable either in combination with a gas heating arrangement for the oven as aforesaid, or for the sole purpose of heating the oven or the stove top thereabove, there being provisions for selectively governing the path of circulation of the oil burner products of combustion in either in-

stance so as to most fully utilize the heating effect thereof.

Referring to the drawing, the reference numeral 1 generally indicates the combined range of my invention which consists of a suitable well insulated casing divided by partitions 2, 3 into a plurality of compartments, namely, the liquid burner compartment 4 at the left as viewed in Fig. 1, the central oven and oven heating compartment 5, and the compartment 6 at the right, which may be used for storage or other purposes.

The partition 2 is common to the liquid burner and oven compartments and is non-insulated for the ready transfer of heat from the former to the latter. It will be noted that partition or wall 2 terminates in spaced relation to the top of the casing, thereby defining a communicating top flue passage between the burner and oven compartments.

Referring to Fig. 1, it will be noted that the range has a cooking or stove top 61 including an oil or liquid fuel cooking section 62 over the oil or liquid burner compartment provided with stove lids 63, and a gaseous fuel section 64 provided with grids 65 heated by gas burners 7 in the burner space 8. This last named space is insulated from the oven compartment 5 by an insulated wall 81 and the partition 3 also has insulation 82 thereon insulating storage compartment 6 from the oven. The various compartments are closed by insulated hinged doors 10 illustrated in Fig. 2 and the rear wall 181 of the range is likewise fully insulated.

The oven of the present construction is defined by the side partition 2, a top sheet metal wall 11, the side wall 12, and the non-insulated floor 13.

It will be noted that the oven is surrounded on three sides by a flue passage communicating with the top of the oil burner compartment, including a top horizontal reach 14 between the insulated wall 81 and top wall 11 of the oven, a vertical reach 15 on the side opposite the oil burner compartment and between the side wall 12 of the latter and insulation 82, and a bottom space 16 beneath floor 13. Baffles 17 are disposed vertically in the side flue reach to augment the uniformity of heating of the oven side wall 12, and the oven is provided with insulation 18 on its top wall and further insulation 19 on the upper half of side wall 12 to insure that the oven will not be excessively heated at its top by the relatively hot products of combustion as they first emanate from the oil burner, but that, on the contrary, the heat will be uniformly transferred to the oven without the occurrence of local "hot spots."

That this is the actual effect in operation has been proved by thermometer tests at many points inside the oven.

In the operation of the oven a regenerative heating action takes place which renders the same exceedingly efficient. Thus, whereas in a standard test in certain previous combination ranges 27,000 B. t. u. have been required to heat the oven to a predetermined temperature (500°) in a predetermined time (18 min.), and in a good gas oven 22,000 B. t. u., in my combined range as illustrated and described the same heating in the same time can be had with about 12,500 B. t. u. I consider that the reason for this is that the oven top is well insulated to prevent wasteful discharge of the heat therethrough and that there is no cold oven bottom to contribute its wasteful effect. Heat is transferred from the traveling products of combustion of the oil burner with great efficiency and without excess carrying away of oven heat by high velocity traveling gases; on the contrary, these gases are caused to transfer their heat to the oven mainly at a point where their velocity of travel has been reduced substantially.

The floor of the oven is provided with an opening in communication with a cylindrical vertical combustion chamber or duct 21 of substantial diameter extending through oven bottom space 16 and a gas burner 22 for the oven is disposed at the lower end of this duct. A plate 23 having a large number of perforations therein is interposed in the duct between the burner and oven for the purpose of distributing the heat evolved at the burner and transferring the same in a uniform, non-localized manner to the interior of the oven. Moreover, a baffle 24 is disposed above the conduit to further contribute to the uniform warming of the oven interior. The insulated rear wall 18 is provided with a vent or opening 25 to the oven communicating with the range flue or with atmosphere and having a suitable adjustable vent plate 26 therein for regulating the escape of products of combustion from the oven.

The annular chamber or space 16 beneath the oven and constituting part of the flue passage for the products of combustion from compartment 4 surrounds the duct 21 (see Figs. 1 and 3) and is provided with a vertical baffle 29 to direct the said products around the duct or gas combustion chamber 21 in the direction indicated by the arrows. In this manner, a very uniform and thorough circulation of the products of combustion beneath the oven floor 13 is assured, following which the products of combustion pass out through an opening 30 in the insulated oven rear wall into the flue 31 of the range, said flue 31 being shown in horizontal section in Fig. 3. This opening 30 is controlled by a plate closure 32 having apertures 33 therein, the plate being manually positioned to fully open or partially close opening 30 by means of a manually controlled toggle instrumentality 34 which is indicated in Fig. 3, but which is not illustrated in further detail for the reason that the specific construction thereof forms no part of the present invention. The purpose of employing this apertured manually shiftable closure plate will be referred to in the description to follow. It should be noted that the floor of the annular space 16 is well insulated by suitable material 35 to prevent heat loss downwardly beneath the space.

Though I have illustrated and described and shall refer in the specification to follow to a con-

struction employing an oil burner unit 28 of the sleeve type in the heating compartment 4, since several distinct advantages are presented by this type, and because the mounting for the unit to be described eliminates the difficulty ordinarily experienced in servicing this type unit, it will be evident to those skilled in the art that the above described provisions for heating or augmenting the heating of the oven have application in the event any other type burner or heater is substituted for the unit 28. Thus, a solid fuel or gaseous fuel burner construction might be incorporated in compartment 4 and the insulating and flue passage arrangement associated with the oven would function just as effectively in providing a uniform non-localized supplemental oven heating action. This will also be recognized to be the case regardless of the particular type of heating means employed primarily to heat the oven and represented in the embodiment disclosed by the gas burner 22. Regardless of the particular heating instrumentalities employed, the products of combustion are circulated from the compartment 4 around the oven in a manner to secure a very uniform heating thereof. The insulating 18, 19 arranged on the top oven wall 11 and top portion of the side wall 12 prevent undue heating of the oven by the relatively hot gases adjacent the same and the non-insulated wall portions and floor enable the less intense heat from the side and bottom of the combustion chamber 4 and the cooler circulating gases to be transferred effectively to the oven interior. Extensive tests with a thermocouple have proved conclusively in an actual embodiment of the invention that the oven interior is devoid of "hot spots," which enables products to be baked therein with highly uniform and satisfactory results.

The oil burner compartment 4, as is clearly illustrated in Figs. 1 and 2, is provided with a pair of inwardly extending angle iron brackets 36 welded to the opposed side walls of the compartment, which brackets are reversely bent at their ends to provide opposed channeled ways 37 extending the entire front-to-rear length of the said compartment and slidably receiving the oil burner unit, which is generally indicated by the reference numeral 28. At the bottom of compartment 4 there is disposed an air intake member 38 having associated therewith a closure plate 39 adjustable on a screw 40 to any desired vertical position relative to the openings in the intake, whereby the said intake may be practically completely shut off, as when the liquid fuel or oil burner unit 28 is used in conjunction with the oven gas heater, or fully opened, as in Fig. 1 when the oil burner is used alone for heating the cooking plates 63 or cooking implements disposed over the openings normally covered thereby. The variable adjustment of plate 39 as well as other draft regulating instrumentalities in the range will be further alluded to in the description to follow in connection with the operation of the range.

The brackets 36 and ways 37 thereon in effect divide the oil burner compartment into the lower air intake space 41 and an upper combustion chamber in which the oil burner unit 28 is mounted. This unit comprises a frame having the elongated angled sheet metal supporting plates 42 to which are welded the ribbed and reinforced burner supporting plate or table 43, constituting an extremely strong and rigid support for the burners highly resistant to distortion under the

substantial changes in temperature to which it is subjected. The plates 42 have the lower ends thereof turned inwardly at 44 to provide slides receivable in ways 37 and thereby enabling the unit 28 to be slid longitudinally of the brackets 36 for removal and cleaning when desired.

The reference numeral 45 is employed to designate a pair of oil burners of conventional sleeve type having the removable perforated top mixer tubes or chimneys 46 associated therewith. These are of triple construction, including plural concentric elements and wicks associated therewith, but the particulars of construction have not detailed. Burners 45 are mounted on supporting frame 43 by means of adjustable threaded legs 47 which are manipulated at the time of installation to bring the burners in the exactly level position which is necessary for the most effective operation thereof. The burner oil feed pipes 48 extend downwardly through openings in the support plate 43 and are connected to the supply pipes 49 which extend rearwardly of the unit.

At its rear end, the support plate is secured by welding, bolting or the like to an insulated closure 50 which has a stepped periphery receivable in a correspondingly stepped aperture in the insulated rear wall of the oil burner compartment, which is but a part of the insulated rear wall 181 of the range. Closure 50 has mounted on and projecting from the external side thereof a sheet metal bracket or ledge 51 for the oil reservoir 52 including an inverted tank 53 removably receivable in a feed pan or sump 54 which is connected at 55 to the oil supply pipe 48. The flow of liquid fuel from the reservoir is controlled by a valve 57 in fitting 571 which is a part of the fuel supply connections, and valve 57 is controlled by mechanical connections 58 including a flexible shaft and a hand piece 581 disposed at the front of the casing.

At its front end, the oil burner unit for burner 22 has a sheet metal closure 56 which is fixedly but removably secured by means of a screw 561 to the front wall of the range casing inside the door 10 for the oil heating compartment 4.

As clearly illustrated in Fig. 1, the oil burner combustion chamber 4 is in full communication with the horizontal reach 14 of the flue passage for circulation of products of combustion of the burner over and around the oven to heat the same uniformly in the manner described. It will be appreciated that there is considerable transfer of heat to the oven on the left hand side thereof by conduction through uninsulated partition or wall 2 separating the oven and oil burner combustion chamber 42. The rear wall of the range is provided with an opening 58 communicating the range flue with flue passage or reach 14 and controlled by an adjustable closure 60. The opening 58 is left unobstructed whereby the oil burner products of combustion normally flow therethrough to flue 31 when the oil burner is being used alone to heat the cooking plates 63 disposed above its combustion chamber, but in the event the oil burner is used in conjunction with the gas heated stove, member 60 is closed to enable the products of combustion of the burner to circulate through the flue passages 14, 15, and 16 to the flue as described. All of the openings 58, 28, and 30 in communication with the aforesaid circulating flue portions, the oven interior and the oven floor heating space, respectively communicate when unobstructed with the flue 31.

In operation, with the oil or other burner unit

28 employed alone to heat the stove top plates 63, the control 39 for the oil burner air intake 38 is elevated fully to the position illustrated in Fig. 1 and the opening 58 to the flue is also fully opened for assuring ample supply of air for combustion. In the event the oven is also used, however, closure 38 is adjusted toward closing position until only a slight air leakage takes place through the intake 38 into the oil burner compartment 4. The flue closure 60 is closed and the apertured plate 32 controlling flue opening 38 is likewise closed or partially closed. The purpose of this is to prevent an excessive draft or blast through the flue reaches or passages 14, 15 such as would tend to cool off excessively the oven surfaces adjacent the passages and to maintain a supply of heated air traveling slowly therethrough. In this manner, not only are all of the thermal units evolved at the gas burner 22 utilized, but also the heat of the circulating products of combustion from the oil burner is employed to the fullest extent. Moreover, there are no "hot spots" in the oven. The apertured gas control plate 23 and baffle 29 for the gas burner 22, plus the provision of insulating means at the top and top of side of the oven insure that the latter will not be non-uniformly and excessively heated at any part interiorly thereof, as stated above, but that, on the contrary, the whole will be very uniformly heated. The thermal efficiency of the foregoing construction is exceedingly high, a far greater heating output being possible for a given total fuel input than in other combined range constructions of which I am aware.

35 I have illustrated and described my improvements in an embodiment which is very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent is:

45 1. In a range, the combination of a casing provided with a burner chamber and an oven disposed at the side of said burner chamber, said chamber and oven having a vertical non-insulated wall common to both and terminating in 50 spaced relation to the top of the casing, said oven being provided with an oven top and with an insulated top, means disposed in spaced relation to said oven top and coacting therewith to provide a flue space at the top of the oven in 55 communication with said burner chamber, said means being insulated at least in part, the side wall of said oven remote from said burner chamber having an insulated upper portion and a non-insulated lower portion, said casing having a vertical insulated partition spaced from said side wall 60 providing a flue space at the side of the oven communicating with said flue space at the top of said oven, said oven having a non-insulated bottom, an insulated casing bottom portion spaced 65 from said oven bottom providing a flue space below the oven communicating with the flue space at the side of the oven, a centrally disposed gaseous fuel combustion chamber in communication with the bottom of the oven and entirely surrounded by said bottom flue space, and a baffle 70 in such bottom flue space for directing the products of combustion circulating from said burner chamber around the said gaseous fuel burner combustion chamber a flue outlet for exit of products of combustion from said casing before pas-

sage beneath said oven, and a second flue outlet for exit of products of combustion from said casing after passage beneath said oven.

2. In a range, the combination of a casing provided with a burner chamber and an oven disposed at the side of said burner chamber, said chamber and oven having a vertical non-insulated wall common to both, said oven being provided with an oven top and with an insulated top, means disposed in spaced relation to said oven top and coacting therewith to provide a flue space at the top of the oven in communication with said burner chamber, the side wall of said oven remote from said burner chamber having an insulated upper portion and a non-insulated lower portion, said casing having a vertical insulated partition spaced from said side wall providing a flue space at the side of the oven communicating with said flue space at the top of said oven, said oven having a non-insulated bottom, an insulated casing bottom portion spaced from said oven bottom providing a flue space below the oven communicating with the flue space at the side of the oven a flue outlet for exit of products of combustion from said casing before passage beneath said oven, and a second flue outlet for exit of products of combustion from said casing after passage beneath said oven.

3. In a range, the combination of a casing provided with a burner chamber and an oven disposed at the side of said burner chamber, said burner chamber and oven having a vertical non-insulated wall common to both and terminating in spaced relation to the top of the casing, said oven being provided with an oven top and with an insulated top, means disposed in spaced relation to said oven top and coacting therewith to provide a top flue space, said top flue space communicating with said burner chamber, the side wall of said oven remote from said burner chamber having an insulated upper portion and a non-insulated lower portion, said casing having a vertical insulated partition spaced from said side wall providing a side flue space communicating with said top flue space, said oven having a non-insulated bottom, an insulated casing bottom portion spaced from said oven bottom providing a flue space below the oven communicating with the side flue space a flue outlet for exit of products of combustion from said casing before passage beneath said oven, and a second flue outlet for exit of products of combustion from said casing after passage beneath said oven.

4. In a range, the combination of a casing provided with a burner chamber and an oven disposed at the side of said burner chamber, said burner chamber and oven having a vertical non-insulated wall common to both, said oven being provided with an oven top and with an insulated top, means disposed in spaced relation to said oven top and coacting therewith to provide a top flue space, said top flue space communicating with said burner chamber, the side wall of said oven remote from said burner chamber having an insulated upper portion and a non-insulated lower portion, said casing having a vertical partition spaced from said side wall providing a side flue space communicating with said top flue space, said oven having a non-insulated bottom, an insulated casing bottom portion spaced from said oven bottom providing a flue space below the oven communicating with the side flue space a flue outlet for exit of products of combustion from said casing before passage beneath said oven, and a second flue outlet for exit of products of

combustion from said casing after passage beneath said oven.

5. A combined range comprising an insulated casing having a plurality of compartments, one of which constitutes an oven having bottom, top, and side walls, means defining a circulation space beneath said oven bottom said space being provided with baffle means to direct the circulation of the products of combustion therethrough, a burner unit disposed in a burner unit compartment adjacent the oven compartment, said burner unit compartment including a combustion chamber in which said burner unit is disposed, said space beneath the oven being connected with said combustion chamber through a vertical passage adjacent the side wall of the oven remote from the burner unit compartment and a horizontal passage over the oven top wall, whereby products of combustion of said unit circulate over, around, and under the oven, said oven having insulating material on the top wall thereof and on the uppermost portion only of the side wall remote from the burner unit compartment, and means including an adjustable air intake for the burner chamber and controllable flue outlets for said casing for selectively controlling the circulation of the products of combustion of said unit at low velocity through said passages and space.

6. A combined range comprising an insulated casing having a plurality of compartments, one of which constitutes an oven having bottom, top, and side walls, means defining a circulation space beneath said oven bottom, a burner unit disposed in a burner unit compartment adjacent the oven compartment, said burner unit compartment including a combustion chamber in which said burner unit is disposed, said space beneath the oven being connected with said combustion chamber through a vertical passage adjacent the side wall of the oven remote from the burner unit compartment and a horizontal passage over the oven top wall, whereby products of combustion of said unit circulate over, around, and under the oven, said oven having insulating material on the top wall thereof and on the uppermost portion only of the side wall remote from the burner unit compartment, and adjustable means for controlling the circulation of the products of combustion of said unit at low velocity through said passages and space a flue outlet for exit of products of combustion from said casing before passage beneath said oven, and a second flue outlet for exit of products of combustion from said casing after passage beneath said oven.

7. A combined range of the type described having a fuel burner compartment and an oven disposed in side-by-side non-insulated relation, said compartment including a combustion chamber having a burner unit therein, means defining connected horizontal and vertical passages in communication with said combustion chamber for circulating products of combustion from said combustion chamber respectively along the top and the side of said oven remote from said compartment, said oven being provided with a top insulated wall and a side wall insulated on the upper part separating said oven from said horizontal and vertical passages, respectively, means defining a space beneath the oven in communication with said vertical passage and in non-insulated heat transfer relation to the bottom of said oven for the circulation of gases from said combustion chamber, said oven having a combustion chamber extending through said space, and an oven heating element in communication with

said last named chamber a flue outlet for exit of products of combustion before passage beneath said oven and another flue outlet for exit of products of combustion after passage beneath said oven.

8. A combined range of the type described having a fuel burner compartment and an oven disposed in side-by-side non-insulated relation, said compartment including a combustion chamber having a burner unit therein, means defining connected horizontal and vertical passages in communication with said combustion chamber for circulating products of combustion from said combustion chamber respectively along the top

and the side of said oven remote from said compartment, said oven being provided with a top insulated wall and a side wall insulated on the upper part separating said oven from said horizontal and vertical passages, respectively, and means defining a space beneath the oven in communication with said vertical passage and in non-insulated heat transfer relation to the bottom of said oven for the circulation of gases from said combustion chamber a flue outlet for exit of products of combustion before passage beneath said oven and another flue outlet for exit of products of combustion after passage beneath said oven.

WILLIAM T. CALEY.
